APPARATUS FOR GRINDING THE WORN
ENDS OF VALVE TAPPETS AND THE
LIKE

Henry Robert Billeter, Highland Park, Ill., assignor to Ammeo Tools, Inc., North Chicago, Ill., a corporation of Illinois

Application February 17, 1950, Serial No. 144,648

5 Claims. (Cl. 51—241)

1

My invention relates to grinding apparatus and it has to do particularly with apparatus for grinding the worn ends of valve tappets commonly employed in internal combustion engines of the automotive type, particularly valve tappets of the type employed in side valve engines. My invention also has utility in other instances where similar problems are to be met, for example, in the grinding of the worn ends of rocker arms such as are used for imparting thrust to the valve stems of overhead valve assemblies.

Heretofore, in processing or regrinding the ends of valve tappets it has been customary to completely remove the valve tappets from the cam shaft follower within which they are threadedly received, but this has been a time-consuming operation. Also, in automotive engines of recent design the valve tappets are threadedly received in the cam follower shank by a forced threaded fit wherein the pitch of the threads on the valve tappet stems varies with respect to the pitch of the internal threads provided in the cam follower stem. Thus, repetitious removal of the valve tappet invariably causes wearing of the threads on either the valve tappet or the cam follower stem with a consequent loss of the desired binding action when the tappets are restored to their position in the engine.

To overcome the foregoing limitations, attempts have been made to process the worn ends of the valve tappets while the same remain in position in the automotive engine, but without success. One common expedient currently resorted to is the removal of the valve and its stem from the valve guide overlying the valve tappet and the passage through the guide of a rotary grinding tool, the lower end of which has thereon an abrasive material. Rotation of the grinding tool within the valve guide when in contact with the upper end of the valve tappet is purported to effect the desired valve tappet processing operation. However, due to the fact that the axis of rotation of the abrasive grinding surface coincides with the axis of the valve tappet, the outer circumferential regions of the abrasive move at a higher speed and impart a greater abrading action than the inner regions thereof so that the extreme central region of the surface to be ground receives practically no abrasive action whatsoever. Furthermore by such a grinding operation very little of the expended abrasive or of the removed metal can be expelled from the end of the tappet and the net result is that when the grinding operation is terminated a central nob or hump is left on the end of the valve tappet.

2

The principal object of my invention is to provide a novel grinding means adapted for grinding worn valve tappets without removing them from their assembled position in the engine.

Another object is to provide a portable grinding device of the foregoing character adapted to operate upon the ends of worn valve tappets to effect a uniform grinding operation over the entire surface thereof, and which receives its support from a stationary part of the vehicle engine and derives its proper alignment with the end of the valve tappet from the axis of the valve guide employed in connection with the usual valve instrumentalities of the internal combustion engine.

Still another object is to provide a grinding device of the foregoing nature which may conveniently derive its power from a small portable electric drill of the type invariably forming a parcel of the ordinary garage or mechanic's equipment.

A further object is to provide a grinding device of this character which is extremely compact and which, as a consequence, may be manufactured in very small dimensions, thereby enabling the same to be conveniently applied to all of the valve tappets ordinarily encountered in an internal combustion engine including the end tappets in the valve chamber which are less accessible than the medial valve tappets.

Additional objects are to provide a grinding apparatus which is comprised of a minimum number of moving parts, and which therefore is unlikely to get out of order; one which is rugged and durable; one in which the moving parts thereof are enclosed within a casing and which are therefore protected against contamination by foreign material, yet which may readily be removed therefrom for the purpose of inspection or repair; one in which the actual abrading element *per se* is readily removable for the purpose of replacement; one which may be manufactured at a relatively low cost; and one which otherwise is well adapted to perform the services required of it.

Other objects and advantages will appear as this description progresses and by reference to the drawing wherein—

Fig. 1 is a fragmentary sectional view taken transversely through a portion of an internal combustion engine in the vicinity of the valve chamber thereof and showing my improved valve tappet grinding device applied to a valve tappet for grinding purposes;

Fig. 2 is an enlarged sectional view taken substantially along the line 2—2 of Fig. 1; and

Fig. 3 is a sectional view taken substantially along the line 3—3 of Fig. 2.

Referring now to the drawing, and in particular to Fig. 1, a fragmentary portion of an internal combustion engine is shown partly in section and includes the usual cylinder block 10 from which the cylinder head has been removed. A valve opening or port 12 which may be an exhaust port leading to the exhaust passage 14 is adapted to be controlled in the usual manner under the influence of a valve 16 (shown in dotted lines) and including a cylindrical valve head 18 and stem portion 20 which is adapted to be guided in the vertical bore 22 of a valve guide 24 secured in a bore 26 provided in the block 10 and extending between the exhaust passage 14 and the valve chamber 28. The cylinder 30 in which a piston 32 is slidably disposed is separated from the valve chamber 28 by means of a wall 34 which merges into a hub portion 36 having disposed therein the usual tap- 10 pet aligning sleeve 38 which in turn has slidably disposed therein a cam follower 40, the lower end of which rests upon one of the cams 42 carried by the cam shaft 44 contained within the engine crank case 46.

The cam follower 40 includes a stem portion 48 having a threaded bore 50 formed in the upper end thereof and which is adapted to threadedly receive therein the split threaded shank portion 52 of a valve tappet 54 having formed thereon the usual polygonal adjusting element 56, above which there is disposed the operative thrust surface 58 which is designed for engagement with the extreme lower end of the valve stem 20.

The valve stem, when the valve 16 is in assembled position in the block 10, carries at its lower end a cup-washer 60 which is situated upon the usual half-moon or other similar retainer 62. A spring 64 surrounds the valve stem 20 and guide 24 and bears at its upper end against a stationary surface provided on the block 10 and at its lower end it is received within the cup-washer 60 to maintain the proper tension upon the valve tending to normally close the valve port 12.

The improved grinding apparatus comprising the present invention is comprised of a tappet grinding assembly designated in its entirety at 72 (Fig. 1) and of a cooperating detachable drive shaft or spindle 74, the latter being preferably formed of hardened steel and of such diameter that it fits snugly within the bore 22 provided in the valve guide 24 for rotary and sliding movement thereon. It will be understood, of course, that when the drive shaft or spindle 74 is passed through the guide 24 for cooperation with the assembly 72, it is necessary to remove the valve 16 and its associated parts including the spring 64, cup-washer 60 and half-moon retainer 62 from the block 10.

The tappet grinding assembly is shown in detail in Figs. 2 and 3 and includes a gear carrier in the form of a cylindrical housing 76 having a top wall 78, a bottom wall 80 and a cylindrical side wall 82. The bottom wall 80 is provided with a cylindrical opening 84 therein in which there is inserted a cup-shaped member 86 having an annular retaining flange 88 for retaining the member 86 within the opening 84. The lower end of the cup-shaped member 86 projects outwardly of the housing 76 and is provided with a smooth polished bearing surface 90 designed for engagement with the upper surface 92 of an abrasive disc or wheel 94 in a manner and for a purpose that will be set forth presently.

The cup-shaped member 86 forms a bearing for

the lower end or hub portion 96 of a driving gear 98 which is rotatably disposed within the housing 76. The upper end or hub portion 100 of the gear 98 is rotatably journaled in a plug or cap 102 having a circumferential groove 103 formed therein and which is received in a circular opening 104 provided in the top wall 78 of the housing 76. The groove 103 is designed for reception of the ends of a pair of set screws 105 which are threadedly received in the housing 76 and which serve to retain the plug or cap 102 in position within the opening 104. The driving gear 98 meshes with a driven gear 106 rotatably disposed in the housing 76 and the axis of which extends in a direction parallel to the axis of the gear 98. The gear 106 is keyed or otherwise secured to the medial region of a driven shaft 108 having a reduced end portion 109 rotatably journaled in an opening 110 provided in the top wall 78. A groove 111 formed near the upper end of the reduced end 109 of the shaft 108 is adapted to receive a slotted retaining collar 112 therein to assist in retaining the shaft 108 in position in the housing 76. A bearing washer 113 is disposed between the retaining collar 112 and the upper surface of the housing 76. An enlarged portion 114 is formed on the shaft 108 and is rotatably journaled in an opening 116 provided in the bottom wall 80. An enlarged circular head 118 is formed on the shaft 108 and occupies a position outside of the housing 76 beneath the bottom wall 80 thereof. The head 118 is provided with a clamping surface 120 which cooperates with a similar clamping surface 122 provided on the slotted head 124 of a clamping stud 126 threadedly received in a socket 128 provided in the enlarged portion 114 of the shaft 108. The abrasive disc 94 is of circular design and is adapted to be received between the clamping surfaces 120 and 122 and is of sufficient diameter and extent that when in position in the assembly 72 it underlies the bearing surface 90 of the cup-shaped member 86 in close proximity thereto.

The driving gear 98 is provided with a bore 130 extending therethrough and a cross pin 132 extends across the lower end of the bore 130 and is designed for register with a cut-away portion 134 provided in the lower end of the driving shaft 74 when the latter is received within the bore 130. The cross pin 132 and cut-away portion 134 of the shaft 74 provide an effective means for transmitting torque from the driving shaft 74 to the driving gear 98. A handle 136 is threadedly received in an opening 138 provided in the housing 76 and serves as a reaction member to prevent rotation of the housing 76 when the assembly 72 is in actual use and also serves as a manipulating member whereby the grinding apparatus may be readily transferred from one valve tappet to another in the valve chamber 28.

In the operation of the tappet grinding apparatus when it is desired to perform a complete tappet grinding operation on an automotive vehicle engine, the various valves 16, together with their retaining means including the spring 64, cup-washer 60 and retainer 62, are removed from the engine and a particular tappet, such as the tappet 54, is selected for processing. The drive shaft or spindle 74 is projected downwardly through the bore 22 provided in the valve guide 24. Meanwhile the assembly 72 is positioned in substantially the position illustrated in Figs. 1 and 3 with the underneath surface of the abrasive disc 94 resting on the upper worn end of the tappet 54. The shaft 74 is then introduced vertically into the bore 130 provided in the gear

98 and the cross pin 132 may be brought into register with the notch 134 by rotating either the drive shaft 74 or by swinging the housing 76 of the assembly 72 about the axis of the tappet. A source of power, as for example the chuck C of a conventional electric hand drill (not shown), is applied to the upper end of the drive shaft 74 and with the operator holding the assembly 72 against rotation by means of the handle 136, the drive shaft 74 is caused to rotate, thus turning the gears 98 and 106 and consequently rotating the abrasive disc 94. The underneath surface of the disc 94 is coated with a suitable abrasive material which frictionally engages the worn upper surface of the tappet 54 during the grinding operation. The disc 94 may be formed of horn fiber, Bakelite or a similar material having wear-resistant characteristics and may possess a certain degree of flexibility whereby the underneath surface 90 of the cup-shaped member 86 may, by downward pressure on the housing 76 applied to the handle 136, force the abrasive surface of the disc 94 into engagement with the worn tappet surface. The abrasive element may, however, be formed as a rigid, unyielding member, in which case its inherent rigidity may be relied upon for the necessary abrasive pressure and the cup-shaped member 86 may then serve merely as a thrust member. After a few revolutions of the abrasive disc 94 the valve tappet 54 is completely processed and the upper surface thereof will be found to be smooth. Application of power to the drive shaft 74 may then be discontinued and the drive shaft 74 removed from the bore 22 without detaching the same from the chuck C. The drive shaft 74 may then be applied to a different guide and the operation repeated for processing the next selected tappet.

I believe that the construction and operation of my invention will be well understood from the foregoing description. It will be clear that I have provided a simple and inexpensive tappet grinder adapted for grinding valve tappets and the like while they are in assembled position in the engine, thereby reducing the cost of the grinding operation.

I claim:

1. In combination, an internal combustion engine block having a valve guide formed with a cylindrical bore, a valve-actuating element mounted on said block with a face spaced from one end of and in alignment with said bore, and a grinder comprising a casing disposed between said face and said one end of said bore, a drive member mounted in said casing and having an axial bore therein in alignment with the bore of said valve guide, a rigid drive spindle extending through the bore of said valve guide and projecting therefrom at one end for connection with drive means and projecting at the other end into the bore in said drive member, means between said spindle and said drive member non-rotatably connecting them while permitting detachment of said spindle merely by outward axial movement thereof, a driven member rotatably mounted in said casing and drive-connected with said drive member and having its axis parallel with and displaced laterally from the axis of said drive member, and a circular rotatable abrasive member carried by said driven member and disposed exteriorly of said casing, said abrasive member being of such diameter that its periphery is disposed in alignment with the axis of said drive member.

2. A device of the class and for the purpose described which comprises a casing, a drive member rotatably mounted in said casing and having an axial bore therein, a drive spindle having one end snugly projecting into said bore, means between said spindle and said drive member non-rotatably connecting them while permitting detachment of said spindle merely by outward axial movement thereof, a driven member rotatably mounted in said casing and drive-connected with said drive member and having its axis displaced laterally from the axis of said drive member, a circular rotatable abrasive member carried by said driven member and disposed exteriorly of said casing in a plane at right angles to the axis of said drive member and of such diameter that its periphery is disposed in axial alignment with said drive member, and thrust means carried by said casing and disposed between the peripheral portion of said abrasive member and said casing in position to maintain the peripheral portion of said abrasive member at substantially right angles to the axis of said drive member when the former is engaged with a workpiece.

3. A device of the class and for the purpose described which comprises a casing, a drive member rotatably mounted in said casing and having an axial bore therein, a drive spindle having one end fitted in said bore, means between said spindle and said drive member non-rotatably connecting them while permitting detachment of said spindle merely by outward axial movement thereof, a driven member rotatably mounted in said casing and drive-connected with said drive member and having its axis displaced laterally from the axis of said drive member, a rotatable, circular and flexible abrasive member carried by said driven member and disposed exteriorly of said casing with its periphery disposed in alignment with the axis of said drive member, and thrust means carried by said casing in alignment with the axis of said drive member in position to engage the peripheral portion of said abrasive member to maintain said peripheral portion at substantially right angles to the axis of said drive member when said abrasive member is engaged with a workpiece.

4. A device of the class and for the purpose described which comprises a casing, a drive member rotatably mounted in said casing and having an axial bore therein, a rigid drive spindle having one end snugly projecting into said bore and its other end extending from the casing for connection with driving means, means between said spindle and said drive member non-rotatably connecting them while permitting detachment of said spindle merely by outward axial movement thereof, a driven member rotatably mounted in said casing and drive-connected with said drive member and having its axis parallel with and displaced laterally from the axis of said drive member, and a rotatable, circular and flexible abrasive disc carried by said driven member, said abrasive disc having an outer abrasive surface and an inner smooth surface and being of such diameter that its peripheral portion projects beyond the axis of said drive member, said casing having a pressure surface of substantial area disposed in alignment with and perpendicular to the axis of the drive member and lying substantially in the plane of the inner surface of the abrasive disc when the latter is in flat condition, said pressure surface being thereby positioned for engagement with the peripheral portion of the

disc and maintaining it in engagement with a workpiece.

5. A device of the class and for the purpose described which comprises a casing having a top wall and a bottom wall, said top wall and bottom wall each having an opening with the openings in alignment with each other, a rigid cup-shaped member disposed in the opening in the bottom wall and having its bottom regions projecting outwardly from said casing and presenting a flat pressure surface, a gear having one end rotatably journalled in said cup-shaped member and the other end journalled in the opening in the top wall, said gear having an axial bore therein, a rigid drive spindle having one end snugly projecting into said bore, means between said spindle and said drive member non-rotatably connecting them while permitting detachment of said spindle merely by outward axial movement thereof, said bottom wall having a second opening, a driven shaft rotatably journalled in said casing and projecting downwardly through said second opening, a gear mounted on said driven shaft in mesh with said driving gear, a relatively thin flexible abra-

10 sive disc having a smooth upper surface and an abrasive bottom surface secured to said shaft outside the casing and being of such diameter as to underlie and engage said flat pressure surface, 5 the peripheral region of said abrasive disc being disposed immediately under said pressure surface in position to be forced downwardly by said pressure surface against a workpiece under and in alignment with said pressure surface.
